UNITED STATES PATENT OFFICE.

JAKE R. HIRSCH, OF MEMPHIS, TENNESSEE.

DRAFT-TIMBER ATTACHMENT FOR RAILROAD BOX-CARS.

No. 839,109.

Specification of Letters Patent.

Patented Dec. 25, 1906.

Application filed December 2, 1905. Serial No. 290,030.

To all whom it may concern:

Be it known that I, JAKE R. HIRSCH, a citizen of the United States, residing at Memphis, in the county of Shelby and State of Tennessee, have invented a new and useful Draft-Timber Attachment for Railroad Box-Cars, of which the following is a specification.

My invention relates to certain new and useful improvements in draft-timber attachment for box-cars, and has for its object to provide a device that is very simple and cheap in construction and one in which the draft-timber can be easily and quickly attached or removed as desired.

Another object of my invention is to provide means for attaching the draft-timber to the sill of the car, so that it can be easily and quickly removed and a new one replaced without unloading the car.

Another object of my invention is to provide a bolt-securing means in connection with the sill, so that the bolt can be easily and quickly removed and replaced by new ones when desired without unloading the car, thereby overcoming the difficulties now existing with devices of this character.

A further object of my invention is to provide auxiliary locking means so that the strain on the bolts will be removed and prevent them from bending or twisting.

With these objects in view the invention consists of the novel features of construction, combination, and arrangement of parts hereinafter fully described, and pointed out in the claims.

In the drawings forming a part of this specification, Figure 1 is a perspective view of the sill and draft-timber, showing my device in place. Fig. 2 is a longitudinal section of the same. Fig. 3 is a transverse section of the sill. Fig. 4 is a perspective view of the locking-block, and Fig. 5 is a perspective view of the bolt locking-block.

Referring to the drawings, A indicates one of the sills of the ordinary box-car, which extends the whole length of the same. Spaced openings A' are formed in the sill adjacent each end, having reduced cut-out portions A² extending off to one side. Suitable recesses A³ are formed in the top of the sill surrounding the cut-out portion and in which the oblong block B is adapted to fit. The block B is provided with a recess B', having a slotted bottom B², and upwardly-projecting lugs B³ adjacent each end of the

slot for the purpose hereinafter more fully described.

The bottom of the sill is provided with a transverse groove A⁴, arranged between the openings A, having a centrally circular recess A⁵.

The draft-timber C is provided with openings C' and a transverse groove C², having a centrally circular recess C³, and the groove C² is adapted to register with the groove A⁴ in the sill and in which the block D, provided with opposite outwardly-extending circular members D', is adapted to fit. The draft-timber is secured to the sill by an ordinary bolt, the head of which is seated in the recess B' in the block B and extends downwardly through the cut-out portion A² and through the opening C' formed in the timber, and is securely locked therein by an ordinary nut, and it can be readily seen that when it is necessary to replace a timber or bolt it can be readily done, as the nuts can be unscrewed off the bolts, which will allow the timber to be removed. The bolts can then be shoved up above the lugs in the recess and pulled out through the openings A' and a new one replaced, and it will be seen that the head of the bolt will be locked in the recess, preventing the bolts from turning.

From the foregoing description it will be seen that I have provided a very simple device for securing the draft-timber to the sill, so that the bolt and timber can be very easily replaced when desired and one that is very effective in use as it saves a great deal of labor and time.

Having thus fully described my invention, what I claim as new, and desire to secure by Letters Patent, is—

1. In a device of the kind described, the combination with a sill provided with spaced openings, a transverse groove formed between said openings, of a draft-timber provided with openings and a corresponding groove and locking means adapted to fit in said openings and groove, for the purpose described.

2. In a device of the kind described, the combination with a sill provided with a vertical opening, of a reduced cut-out portion communicating with said opening, a recess formed in the top of the sill surrounding said cut-out portion, and a locking member adapted to be secured in said recess, for the purpose described.

3. In a device of the kind described, the combination with a sill provided with a vertical opening having a reduced cut-out portion communicating therewith, a recess formed around said cut-out portion, of a draft-timber provided with an opening, a locking member secured in said recess, and a bolt carried by said locking member adapted to pass through said openings, for the purpose described.
4. In a device of the kind described, the combination with a sill provided with spaced

openings, having reduced cut-out portions communicating therewith, a recess formed in the top of the sill around said cut-out portion, of a sill provided with openings, a slotted recessed block secured in said recess, and a bolt carried by said block, adapted to pass through the openings in the sill, and timber, for the purpose described.

JAKE R. HIRSCH.
